US00D870296S

(12) **United States Design Patent** (10) Patent No.: **US D870,296 S**
(45) Date of Patent: **** Dec. 17, 2019**

(54) **ULTRASOUND PROBE**

(71) Applicant: **Butterfly Network, Inc.**, Guilford, CT (US)

(72) Inventors: **Matthew de Jonge**, New York, NY (US); **Christopher Thomas McNulty**, Guilford, CT (US); **David Elgena**, Brooklyn, NY (US); **Stephen Christopher**, Philadelphia, PA (US); **Paul Maxted**, Guilford, CT (US); **Jonathan C. Schultz**, Guilford, CT (US); **Benjamin Chopra**, Guilford, CT (US)

(73) Assignee: **Butterfly Network, Inc.**, Guilford, CT (US)

(**) Term: **15 Years**

(21) Appl. No.: **29/677,071**

(22) Filed: **Jan. 16, 2019**
